POLE VAULTING STANDARD

Thomas O. Olsen, Salina, Kans., assignor of one-tenth to Gerald R. Sebree and one-fifth to Milton L. Morrison, both of Salina, Kans., and one-fifth to Kenneth Morrison, Hastings, Nebr.

Filed Oct. 15, 1963, Ser. No. 316,268
15 Claims. (Cl. 272—59)

My invention concerns a standard particularly adapted for pole vaulting. It may be adapted in a lower height for high jumping. Briefly the specific embodiment illustrated includes an upper standard pivotally connected to a lower standard and pivotal between an upright position supporting a rail for vaulting and a lower generally horizontal position convenient to place the rail on its supporting pins. Means are provided for securing the rail in position on its supporting pins until the upper standard is pivoted to its upright position and until it is desirable to release the rail. The single supporting pin on each standard is mounted on brackets adjustable to various positions and supporting the rail in a cantilevered manner from the upper standard so that the hazard of a vaulter falling short and striking the ground, standard or supporting base is minimized.

Few changes have been made in vaulting standards. Field and track competition may be said to be increasingly popular events and improvements in equipment are desirable. The new fiber glass reinforced vaulting poles have resulted in higher vaults and improvements are particularly desirable in vaulting equipment, especially for purposes of safety and for minimizing time taken for replacing dislodged rails, particularly during meets. My invention concerns rather basic changes in vaulting standards to serve those purposes.

During vaulting frequently the rail is struck by the vaulter and falls from its supporting pins on the standards. It is difficult to replace the rail and this is an unduly time consuming operation during track and field meets. The task of replacing the rail has been rendered increasingly difficult as higher vaults have been achieved, now passing the seventeen foot mark. Replacing the rail is difficult even at the lower levels such as nine to fifteen foot marks in high school competition. The difficulty of replacement is increased on windy days. The rail is often blown from its supporting pins during periods when the wind is strong or has severe gusts, so the problem is not only one of the rail being dislodged by a vaulter. Practice is sometimes abandoned on such days, although operations have to be continued during meets and the rails are replaced time and again. This is particularly unfortunate during meets as the vaulters may grow cold while waiting for the rail to be replaced and to remain in position. Preferably rails are replaced with a minimum of time so that the vaulter will not grow cold ("cold" meaning actual temperature on chilly days and meaning the physiological and psychological reactions to interruptions in efforts on any day).

The objectives of my invention include: reducing the time required to replace vaulting rails and minimizing difficulty from wind; to provide means for lowering the rail supporting means on vaulting standards for direct manual replacement of the rail from the ground, thereby minimizing time of replacement; and to provide means for securing the rail on the place on its supporting pins during raising of the standard, or until vaulting or at all times during practice vaulting, particularly on windy days.

As rails bow between supporting standards, the heights in vaulting cannot be merely measured from the ground level to the supporting pins. Instead the measurement is made for each rail for the top of the take-off box to the middle of the rail. As long as the rail is positioned with the same side down, this one measurement is suf-

2

ficient for purposes of calibration of indicated versus actual heights, until the rail is broken or bent. This means the support for the pins on a vaulting standard has to be adjustable in fractions of inches from the supported base. It is common to space the supporting pins at nine inch intervals which means that adjustable mounting of the pins relative the standard base is indicated even for inch adjustments of heights. It is an object of the invention to provide an adjustable vertical mounting for the rail supporting pins on the standards in an economical and easily operated manner. The implicit assumption in the prior art appears to have been that a series of superimposed pins are needed on each standard and it is a further objective of my invention to devise a structure whereby essentially only one pin is needed on each standard.

When an athlete makes a vault and comes down too close to the rail or on the rail he may even miss the landing pit and he is in danger of striking the standards or the supporting base (or sandbags covering the base). The athlete risks severe injury in such short vaults. Apparently it has been assumed in the prior art that the standards and the rail have to lie substantially in the same vertical plane, and that the landing pit has to lie beyond that plane. It is an object of my invention to support the pins (and the rail thereon) on the standard in a cantilevered manner in the direction of and above the landing pit or the like so that an athlete coming down short may still land in the landing pit and avoid striking the standard, its base or anything other than the prepared landing surface.

Additional objectives and advantages of my structure, including the provision of an easily operated, adaptable and economical structure, will be understood from the following description, read with reference to the drawings, in which:

FIGURE 1 is a side elevational view of a specific embodiment of my improved vaulting standard, the upper standard being shown in a first upright position and a second generally horizontal position.

FIGURE 2 is a view, partly in section, taken on line 2—2 of FIGURE 1.

FIGURE 3 is a view, partly in section, taken on line 3—3 of FIGURE 1.

FIGURE 4 is an enlarged fragmentary view, partly in section, of the valve means in the hydraulic cylinder.

FIGURE 5 is an enlarged side elevational view of the pin supporting bracket and associated structure, the means for securing the rail to the pin being shown in a first securing position and in a second removed position.

FIGURE 6 is an enlarged side elevational view, partly in section, of the area of the structure where the upper standard is pivoted to the lower standard, the upper standard being shown in an upright and in a generally horizontal position.

FIGURE 7 is an enlarged fragmentary view, partly in section, taken on line 7—7 of FIGURE 6, concerning the latching means for the upper standard in its horizontal position.

FIGURE 8 is a face elevational view, fragmentary and on enlarged scale, of the latching mechanism.

FIGURES 9 and 10 are similar and show two positions of the latching mechanism, the views being fragmentary and partly in section.

The following description will describe how the structure illustrated in the drawings meets the objectives of the invention and the advantages thereof. It will be observed from FIGURE 1 that the pin supporting structure on the upper standard is lowered to a convenient position for replacement of the rails. Securing means is provided for securing the rail in place. This not only avoids dislodging during raising but also permits the

rail to be released at the last second during the vaulting on windy days. In practice sessions, particularly on windy days, the rail may be left secured in position, as the vaulter and the coach will be able to tell when the rail has been struck without it actually being displaced from the pins. It will be observed the rail is supported in a cantilevered manner on the landing pit side of the standards to avoid injury to the vaulter if he lands short of the normal landing area. I have devised a landing net used as a substitute for a landing pit and having various advantages in avoiding injury to vaulters, including catching the vaulter if he jumps short, and it is desirable with the use of the landing net to have the rail supported in a cantilevered manner as this in line with other measures for minimizing the chances of injury to the vaulters.

FIGURE 1 shows one of a pair of standards used to support a rail 10, the one shown being on the left hand facing the landing pit, the only difference between the right and left hand being that the pin securing mechanism is positioned on the side of the bracket toward the outside. This is not necessary but is desirable to clear the area between the pins.

Upper standard 12 is pivotally mounted on the upper end of lower standard 14 by pivotal mounting means 16 not shown but preferably including sealed ball bearings. The lower standard is supported by a base 18.

The take-off box 20 of conventional construction is shown in phantom in FIGURE 1. Vaulters have individual preferences as to the distance between the vertical plane of the portion of the take-off box receiving the butt end of the vaulting pole and the vertical plane of the rail. The take-off box 20 is positioned fixed in the ground with its top edge level with the usual concrete supporting surfaces for the standards, so the standards rather than the take-off box have to be adjusted in position as to the separation of the above mentioned vertical planes. I provide for the adjustment of the positions of the standards relative to the take-off box by the structure detailed in FIGURE 1, 2 and 3 in which there is a cast iron footing 22 supporting a pair of channel tracks 24. Lower standard 14 is secured to platform 25 having rods 26 secured thereto having on their ends four rollers 28 running in channel tracks 24. The rollers are not detailed but preferably include sealed ball bearings. The platform is secured in adjusted position along tracks 24 by a screw 30 threaded into the platform and locking by being tightened against the top of footing 22, the screw having a large head for a convenient manual operation. There may be indicia between the platform and the rails for convenient resetting of the location of the standard 14 on base 18. The vaulter positions the pole upright in the vaulting box and then can tell from the distance from rail 10 where he wants standards 14 set. When the indicia is noted as to the location, this can be reset each time the vaulter wants to use the standards.

It will be observed from FIGURES 1 and 6 that upper standard 12 has a first upright position and a second generally horizontal position. It will be understood that the upright position is preferably exactly aligned with the vertical and that the second position might as well be close to the true horizontal. However, for the purpose of the present specification and claims I do not wish to limit the expressions "upright" and "generally horizontal" but wish to have them have their broadest meanings suitable for accomplishing the purposes described, i.e., the expansion "generally horizontal" is meant to encompass lowering the upper standard 12 even to the point its end rests on the ground, although, as above pointed out, a truly horizontal position will be convenient. Other means have been considered for lowering the rail supporting pins to a level for direct manual replacement of the rail on the pins by a man on the ground, but the form of articulation shown is

5
10
15

4
preferred in which an upper standard is pivotally connected to a lower standard and in which the pins are thus lowered by simple pivoting of jointed members.

The pivotal assembly includes a pair of plates 36, 38 secured to upper standard 12 and pivotally supported on lower standard 14 by pivotal mounting means 16 including a tube 40 secured in lower standard 14. Hydraulic piston and cylinder assembly 42 has a piston rod 44 secured to a pin 46 at the lower end of plates 36, 38 and has its cylinder secured to platform 25 by means 48 such as a threaded bolt and nut assembly in a manner permitting some tilting of the cylinder. It will be observed from FIGURES 1 and 6 that the hydraulic piston and cylinder assembly extends and contracts as upper standard 12 is pivoted, forming an extensible-contractable link.

A compression spring 50 between the upper end of the cylinder 52 and the piston 54 normally acts to hold upper standard 12 in its upright position, the contraction of the assembly being limited by an abutment 56 between plates 36, 38 and lower standard 14. Upper standard 12 is lowered against the resistance of the spring by pulling on a line 60 or by grasping the upper standard. The positive acting spring means is preferred to mere counterbalancing of standard 12.

Hydraulic fluid oil is contained in the cylinder 52 but a one way check valve 62 permits flow of hydraulic fluid past piston 54 at a fast enough rate so that lowering of standard 12 is not appreciably retarded. However, check valve 62 acts against movement of the hydraulic fluid in the opposite direction and the fluid is metered through slots 64 in the threaded end of piston rod 44 disposed in piston 54. It will be observed that the farther piston rod 44 is threaded into piston 54 the lower the rate of metering of hydraulic fluid. This means that raising of standard 12 by spring 50 is retarded to a rate governed by the metering of the hydraulic fluid through slots 64. This could be adjusted to a limit of zero movement so that upper standard 12 may be raised as slowly as desired. The purpose of this metering operation is partly to avoid dislodging rail 10 from its position on pins 68 by free acceleration of standard 12 to abutment 56, but means are provided to secure the rail in place and a principal reason for providing for gradual raising of standard 12 is to avoid the shock and damage that might occur if the compression spring were to raise standard 12 without restraint.

It is desirable to secure upper standard 12 in its horizontal position until rail 10 is replaced. Latching is convenient for two man replacement of the rail and is necessary for one man replacement. The latch mechanism 74 is shown in FIGURES 1 and 6 to 10. This includes a spring metal latch piece 76 having a bent outstanding latch portion 78 catching the edge of upper standard 12 at 80. Latch piece 76 is secured to lower standard 14 by screws 82. The structure would be sufficient for latching and release of standard 12 without more, but additional structure is provided for convenient release comprising a ball 84 guided in a slot formed by lips 86 on latch piece 76 crimped around the ball, whereby the ball is movable between the lower initial position shown in FIGURE 9 when standard 12 is secured by latch portion 78 and the upper release position shown in FIGURE 10 abutted to bent latch portion 78 and permitting edge 80 of upper standard 12 to slide over the latch. In other words, the release is operated by moving upper standard 12 downwardly from the position shown in FIGURE 9 until edge 80 passes on the other side of ball 84, whereby, upon release of upper standard 12, edge 80 carries the ball upward with it and slides over the same past the latch and is released. Once the rail is positioned on the two upper standards 12, the standards are released merely by giving them a push downward so that edge 80 passes ball 84. The upper standards then will be raised by spring 50 at a rate determined by the setting

of hydraulic piston and cylinder assembly 42. The whole operation can be accomplished by one man if the rate is low, e.g., he releases one upper standard 12 and quickly moves over to release the other.

Cantilevered support of the rail over the landing pit can be accomplished by other means but preferably is accomplished by the use of slidably mounted brackets, particularly because this integrates with the concept of using a single rail supporting pin and other purposes. Pins 68 are outstanding from brackets 90 supported on upper standard 12 in a cantilevered manner by a pair of square collars 92 slidable on upper standard 12. These are secured by thumb screws 94 threaded into collars 92 and bearing on upper standard 12. Indicia, not shown, is provided between bracket 90 and upper standard 12 for accurate location of the bracket. For example, if the indicia is in increments such as 12, 14, 16 foot marks and inches therebetween, this means if the fifteen foot indicia is aligned on both standards that the pins are at the same level and the rail is approximately fifteen feet from the top of take-off box 20. However, as before indicated the horizontal rails bow between the pins and it is necessary to calibrate for each horizontal rail when it is replaced after a previous rail has been broken or if the rail has been bent during use. The rails may have various cross sections but all forms have at least one flat side so that the rail can be marked as to which side is down. Then a measurement is made between the rail in this position and the top of the take-off box and it is known how far off the reading of the indicia, such as fifteen foot, is from the true distance. If the bowing is one inch then the brackets must be set at fifteen foot one inch to achieve the fifteen foot height. The same allowance can be made at each setting until the rail is bent or replaced.

Bracket 90 has a polygonal shape with a horizontal upper side 96. The lower side 98 is set at a bracing angle, a vertical side 100 abuts upper standard 12 and an outer vertical side 102 supports pin 68. These sides may be made by channel shaped members and may be welded together. A diagonal brace 104 adds additional strength and serves a purpose as a pivot support for securing arm 106. In one model of the invention tested, side 96 had a length of eighteen inches meaning that pin 68 is cantilevered eighteen inches from standard 12. To achieve substantial results, the cantilevering should be a minimum of a foot, and eighteen inches is preferred. The safety purposes of this have been detailed before. Cantilevering of pin 68 in the manner shown is preferred as it minimizes structure adjacent the vertical plane of the rail and economically incorporates with the other functions of adjustment of height and of securing the rail 10 to the pin 68.

Securing or rail 10 to pin 68 preferably is accomplished by the structure detailed in FIGURE 5 in which arm 106 carries a pin finger 110 pivotal between a lower position pressing the rail 10 to pin 68 and an upper removed position. The upper position is best seen in FIGURE 5 and it will be noted that finger 110 in this position has the position and part of the function of a second pin. This is desirable. In previous standards the pins, separated some distance such as nine inches, were superposed. A series of superposed pins are unnecessary. However, vaulters have found occasionally when they strike the rail supported on a lower set of pins, the rail will bounce up against an upper set of pins and come down and remain on the lower set of pins without falling off. Thus vaulters may insist on having the effect of upper and lower pins separated the conventional distance so that the phenomenon may occur occasionally of bouncing of the rail between upper and lower pins without dislodgement and so that a successful vault will be recorded where otherwise the rail would fall to the ground.

Abutments may be provided in the two positions of securing arm 106 and in the disclosure these abutments

may be taken to be pin 120 supporting spring 122 in the upper removed position and to be rail 10 in the lower securing position. Securing arm 106 may be pivoted from the secured position to the released position by pulling on line 60. As before mentioned, line 60 also may be used to pull standard 12 down to its horizontal position. This may be a nylon or other cord secured to the end of arm 106 at 123 and having preferably both temporary securing and weighted means at the lower end at 124 to keep the cord from being blown in the way of the vaulter. Spring 122 extends between pin 120 and securing means 128 on arm 106. The spring will tend to hold finger 110 in position securing rail 10. Finger 110 may be released by pulling on line 60 whereby arm 106 is brought to an upper position and whereby the spring is so disposed, considering friction of the moving parts, that arm 106 will remain in the upper position shown in FIGURE 5.

In operation the upper standards 12 are brought down to the horizontal position and latched, rail 10 is disposed in position and arms 106 are pivoted to the position where fingers 110 secure rail 10 against pins 68. Then the upper standards 12 are released and permitted to raise. On a day that is not windy, line 60 may then be pulled moving arm 106 to release rail 10. On a windy day during a meet two men may operate the cords 60 so as to release rail 10 about the time the vaulter starts his vault. During practice particularly on a windy day the rail may be left in secured position.

The nature, details and operation of my invention, and objectives and advantages thereof, will be understood from the above description. I do not wish to be limited to the specific details shown and described, but instead wish to cover those modifications of my invention which will readily occur to those skilled in the field from knowledge of my invention, which modifications are encompassed within the appended claims.

I claim:

1. Standard means to support with another like standard a horizontal rail for pole vaulting comprising:
  - (a) a base, a standard formed by upper and lower standards and said lower standard upstanding from said base,
  - (b) said upper standard pivotally connected to the upper portion of said lower standard and pivotal from an upright position to a generally horizontal position in an upright plane transverse of said rail, said upper standard in said generally horizontal position extending to the approach side of said rail,
  - (c) means between said upper and lower standards normally biasing said upper standard to said upright position,
  - (d) horizontally outstanding pin means on said upper standard for supporting said rail for disengagement from said pin means if contacted by the vaulter and which rail can be laid thereon in a position out from said standard, whereby said upper standard may be brought to said horizontal position for rail replacement in pole vaulting.
2. The subject matter of claim 1 in which there is a member mounted on said upper standard and adjustable therealong and said pin means includes a pin outstanding from said member and means operative to secure said member in various positions vertically, whereby said rail may be supported at selected levels above the ground.
3. In a standard to support with another like standard a horizontal rail for pole vaulting and the like, said standard having a pin on which said rail is disposed, the improvement, comprising: a member movably mounted on said standard to move between a first position securing said rail to said pin and a second removed position, and means manually operable from the ground operative to move said member between said first and second positions, whereby said rail may be secured in

position against being blown off said pin by the wind or otherwise being dislodged until released by said member.

4. The subject matter of claim 3 in which said member is a finger and in which said finger in said removed position is disposed above said pin in the spaced superposed relation normal to superposed pins on pole vaulting standards. 5

5. Standard means to support with another like standard means a horizontal rail for pole vaulting and the like, comprising: 10

- (a) a base and a lower standard upstanding from said base,
- (b) an upper standard pivotally connected to the upper portion of said lower standard and pivotal from an upright position to a generally horizontal position in an upright plane transverse of said rail, said upper standard in said generally horizontal position extending to the approach side of said rail, 15
- (c) means between said upper and lower standards normally biasing said upper standard to said upright position,
- (d) pin means on said upper standard for supporting said rail.
- (e) means between said upper and lower standards operative to retard movement of said upper standard from said generally horizontal position to said upper position. 20

6. The subject matter of claim 5 in which said means to retard movement includes a fluid piston and cylinder having valving means between opposite sides of said piston, said valving means adjustably metering fluid in the direction in which said fluid passes in raising of said upper standard whereby said movement is adjustably retarded, said valving means permitting substantially free movement of said fluid in the direction in which said fluid passes in lowering of said upper standard. 30

7. The subject matter of claim 6 in which said valving means is housed in said piston and includes a one-way check valve for said substantially free movement of said fluid and includes a restricted opening for said adjustable metering of fluid, said restricted opening being formed by said piston having a threaded bore and threaded piston rod adjustable along said bore, said rod having axially tapered slots in its end within said piston whereby adjustable metering is achieved by threaded adjustment of said rod in said bore, said fluid being a hydraulic fluid oil, said means biasing said upper standard to said upright position being a spring housed in said cylinder and acting between an end wall of said cylinder and said piston. 40

8. Standard means to support with another like standard means a horizontal rail for pole vaulting and the like, comprising:

- (a) a base and a standard upstanding from said base,
- (b) pin means on said standard for supporting said rail,
- (c) adjustable positioning means between said standard and said base for generally horizontal adjustment of said standard in an upright plane transverse of said rail, whereby adjustment in relative positions of the horizontal rail and a take-off box may be achieved, said adjustable positioning means including said base having a footing and a pair of parallel channel tracks mounted on said footing, a platform secured to the lower end of said standard, and rollers on said platform received in said tracks. 55

9. The subject matter of claim 8 in which there is securing means between said platform and the remainder of said base including a manually adjustable screw threaded in said platform and adjustable to bear on a portion of said remainder of said base. 70

10. Standard means to support with another like stand-

ard means a horizontal rail for pole vaulting and the like, comprising:

- (a) a base and a lower standard upstanding from said base,
- (b) an upper standard pivotally connected to the upper portion of said lower standard and pivotal from an upright position to a generally horizontal position in an upright plane transverse of said rail, said upper standard in said generally horizontal position extending to the approach side of said rail,
- (c) means between said upper and lower standards normally biasing said upper standard to said upright position,
- (d) pin means on said upper standard for supporting said rail,
- (e) cantilevering means between said base and said pin means disposing said pin means spaced in said upright plane from a vertical through the location of attachment between said base and said lower standard, said pin means being spaced from said vertical to the landing side of said rail, whereby said rail is supported on said pin means closer to a landing pit or the like to avoid vaulters striking the ground, said standards or said base when they land short of the usual landing area.

11. Standard means to support with another like standard means a horizontal rail for pole vaulting, comprising:

- (a) a base and a standard upstanding from said base,
- (b) pin support means on said standard having a horizontally outstanding pin means for supporting said rail, said pin support means being lowerable to a level whereby a man on the ground may directly manually position a rail on said pin means and raisable to pole vaulting heights,
- (c) securing and releasing means operative to secure said rail on said pin means and to release said rail on said pin means and operable to its releasing position by a man on the ground while said rail is at pole vaulting heights, whereby said rail may be secured in place on said pin means on occasions.

12. The subject matter of claim 11 in which said securing means includes a finger pivotally mounted to be moved between a first position pressing the rail to said pin means and a second removed position.

13. Standard means to support with another like standard means a horizontal rail for pole vaulting, comprising: a base and a standard upstanding from said base, a bracket mounted on said standard and pin means mounted on said bracket, said bracket being slidable on said standard for adjusting pole vaulting rail heights, said bracket being disposed in a plane transverse of said rail and being directed to the landing side of said standard whereby a vaulter making a short landing may not strike the ground, said standard or said base, manually operable means operative to secure said bracket in position whereby said rail may be supported at various distances from the ground, means for lowering said bracket to man height for replacement of a pole vaulting rail on said pin means by a man standing on the ground, and means mounted on said bracket for selectively securing said rail in position on said pin means or releasing said rail.

14. Standard means to support with another like standard means a horizontal rail for pole vaulting, comprising:

- (a) a base and a standard upstanding from said base,
- (b) a bracket on said standard having pin means for supporting said rail,
- (c) an arm pivotally mounted on said bracket and having a finger at one end pivotal between a first position securing said rail to said pin means and a second position removed above said pin means, said pin means consisting of a single pin outstanding on said bracket, said finger in said second removed

position being disposed in the manner of a second pin spaced above said single pin achieving the effect of superposed pins in conventional standards, a spring between said arm and said bracket pressing said finger to said rail in said first position, a line secured to said arm operable from the ground to move said arm to said second position against the resistance of said spring.

15. Standard means to support with another like standard means a horizontal rail for pole vaulting and the like, comprising:

- (a) a base and a lower standard upstanding from said base,
- (b) an upper standard pivotally connected to the upper portion of said lower standard and pivotal from 15 an upright position to a generally horizontal position in an upright plane transverse of said rail, said upper standard in said generally horizontal position extending to the approach side of said rail,
- (c) means between said upper and lower standards 20 normally biasing said upper standard to said upright position,
- (d) pin means on said upper standard for supporting said rail,
- (e) means operative to hold said upper standard in 25 said generally horizontal position including a spring latch member secured to said lower standard and

5

25

having a bent outstanding latch portion catching a portion of said upper standard, a ball and guide means for said ball on said latch member below said bent outstanding latch portion, whereby said latch member may be released by bringing said portion of said upper standard down past said ball whereby on release said portion of said upper standard carries said ball with it as it moves upwards and is cammed by the ball past said bent outstanding latch portion so that said upper standard may return to said upright position under the force of said means biasing said upper standard to said upright position.
